DESCRIPTION

FIG. 1 is a left side perspective view of an electronic drawing device showing my new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a bottom plan view thereof; and,

FIG. 7 is a top plan view thereof.

The broken line disclosure illustrates the environment for the hand-held electronic drawing device and forms no part of the claimed design. Any surface indicia or graphics also forms no part of the claimed design.

1 Claim, 7 Drawing Sheets
